UNITED STATES PATENT OFFICE.

JAMES A. HENAUT, OF EASTHAMPTON, MASSACHUSETTS, ASSIGNOR TO DRAPER CORPORATION, OF HOPEDALE, MASSACHUSETTS, A CORPORATION OF MAINE.

SELVAGE-LOOP RETAINER.

Application filed November 12, 1923. Serial No. 674,337.

To all whom it may concern:

Be it known that I, JAMES A. HENAUT, a citizen of the United States, residing at Easthampton, in the county of Hampshire and State of Massachusetts, have invented new and useful Improvements in Selvage-Loop Retainers, of which the following is a specification.

This invention relates to improvements in looms and has for an object the provision of a selvage loop retainer which may be attached to the loom to form a selvage on cotton fabrics, heavy duck, leno, screen cloth and other woven material, in such a manner as to prevent the filling from pulling tight in the selvage and causing "saw teeth" or filling cuts therein.

Another object of the invention is the provision of a selvage loop retainer which is simple in construction, efficient in operation and may be easily attached to a loom.

With the above and other objects in view, the invention further includes the following novel features and details of construction, to be hereinafter more fully described, illustrated in the accompanying drawings and pointed out in the appended claims.

In the drawings:—

Figure 1 is a plan view showing a portion 30 of a loom with the invention applied.

Figure 2 is a side view of the same.

Figure 3 is a section on the line 3—3 of 35 Figure 1.

Figure 4 is a detail perspective view of 40 the temple carried shaft bearing plate.

Figure 5 is a similar view of the lay carried slide plate.

As the present invention relates only to a particular feature in the construction and 45 operation of the loom, it is sufficient to illustrate and describe only those parts of the loom directly concerned with a preferred embodiment of the invention. A familiar type of temple 10, a portion of the lay 11, and the weft threads 12 and the warp threads 13 are shown in their usual relation.

Secured to the temple by the bolts 14 is a temple shaft bearing plate 15 which carries spaced arms 16 provided with openings 50 17 for the accommodation of a rock shaft 18.

Secured to the temple as indicated at 14 is a temple heel plate 15, the said plate

carrying spaced arms 16 which are provided with openings 17 for the accommodation of a rock shaft 18. 55

Rigidly and adjustably secured upon the shaft 18 is an arm 19, while pivotally secured to the outer end of this arm is loop retaining finger 20, the inner end of which 60 is provided with a hook-shaped portion 21 for engagement through an opening provided in the outer end of the arm 19.

The finger 20 extends through a slot 22 provided in the temple cap 23 of the loom 65 and is guided backward and forward over the temple burr spindles 24. There are usually two long and two short burrs arranged within the temple, but in the case of the present invention the long ones are 70 removed and four short burrs 25 are substituted and the finger 20 engages the ends of these burrs so as to resist any tendency for lateral movement. This finger 20 is 75 preferably guided in its sliding movement in the required path by its connection at its forward end with the arm 19 and by resting upon the rear temple burr spindle 24. The free end of the finger 20 is movable over the weft threads 12 at the fell 80 in a downwardly inclined position and is yieldingly forced in this direction by means of a spring 26 which has one end engaged with the arm 19 and its opposite end engaged with one of the bearing arms 16. 85 Movement of the loop retaining finger in this direction is limited by a stop finger 27 which is adjustably secured to the shaft 18 and engages one of the arms 16.

Adjustably secured upon the outer end of the shaft 18 as shown at 28, is one end of a cam arm 29, this arm and the stop finger 27 acting to hold the shaft 18 against longitudinal movement. The free end of the cam arm 29 is located in the path of the cam 30 which is carried at one end of a plate 31, the latter being adjustably mounted upon the lay 11. 90

In the operation of the invention, after 100 the shuttle has passed the edge of the fabric, as the lay goes back, the loop retaining finger 20 moves rearward over the weft thread, the said finger inclining rearwardly and downwardly. The shuttle in its return movement loops the weft thread over the 105 end of the finger 20, any tendency of the

loop to pull inward toward the edge of the fabric being resisted by the said finger. When the lay moves forward to beat in the thread, the cam 30 engages the cam arm 29 which 5 rocks the shaft 18 and moves the loop retaining finger 20 against the action of the spring 26 and out of the loop of the weft thread just formed. It is of course understood that the mechanism is duplicated 10 upon the opposite side of the loom.

It will be noted that the loop retaining finger is a substantially straight piece of wire having a downwardly curved rear end. This finger slides substantially parallel with 15 the edge of the cloth and moves in a path above the cloth. When this finger is projected rearwardly it passes over the weft beaten in at the fell due to its downwardly curved rear end, its support upon the rear 20 burr spindle and its connection with the swinging arm 19. When the lay beats up the finger is retracted so as to carry its rear end forwardly of the fell and this is effected in the particular construction illustrated by the co-operation of the cam 30 25 and the cam arm 29. The spring 26 acts normally to project the finger rearwardly past and inclining downwardly over the fell. Consequently when the pick of filling or 30 weft is taken toward the side at which the temple is located and this pick is beaten in the finger is carried forwardly of the fell. As the lay retracts or moves back the finger is immediately projected rearwardly down 35 over the weft and as the pick toward the opposite side takes place the weft is looped over and around the finger. The finger is then withdrawn from this loop on the succeeding beat up of the lay.

40 The invention is susceptible of various changes in its form, proportions and minor details of construction and the right is herein reserved to make such changes as properly fall within the scope of the appended claims.

45 Having described the invention what is claimed is:—

1. A loom comprising a temple, a lay 50 movable toward and from the temple, a selvage loop retaining finger mounted in the temple to slide substantially parallel with and above the edge of the cloth adjacent the fell, means acting normally to project the finger rearwardly past and inclining downwardly over the fell, and means acting simultaneously with the beat-up of the lay to 55 retract the finger forwardly of the fell whereby, after the pick of weft toward the side at which the temple is located is beaten in and the lay moves back the finger is projected over the weft and the next pick toward the opposite side loops the weft over and around the finger, which is then withdrawn therefrom on the succeeding beat-up 60 of the lay.

65 2. A loom comprising a temple, a lay

movable toward and from the temple, a selvage loop retaining finger movable substantially parallel with and above the edge of the cloth adjacent the fell, a rock shaft mounted on the temple, an arm on the shaft 70 connected to the finger to effect the operation thereof, a spring connected to the shaft acting normally to project the finger rearwardly past and inclining downwardly over the fell, and a second arm on the shaft extending 75 in the path of the lay and acting when struck by the lay on the beat-up to retract the finger forwardly of the fell, whereby, after the pick of weft toward the side at which the temple is located is beaten in and the lay moves back, the finger is projected over the weft and the next pick toward the opposite side loops the weft over and around the finger, which is then withdrawn therefrom on the succeeding beat-up 80 of the lay.

3. A loom comprising a temple, a lay 85 movable toward and from the temple, a selvage loop retaining finger movable substantially parallel with and above the edge of 90 the cloth adjacent the fell, a rock shaft mounted on the temple, an arm on the shaft connected to the finger to effect the operation thereof, a spring connected to the shaft acting normally to project the finger rearwardly past and inclining downwardly over the fell, a cam plate mounted on the lay and a cam arm on the shaft extending in the path of the cam plate and acting when engaged by the cam plate on the beat-up to 95 retract the finger forwardly of the fell, whereby, after the pick of weft toward the side at which the temple is located is beaten in and the lay moves back, the finger is projected over the weft and the next pick toward the opposite side loops the weft over and around the finger, which is then withdrawn therefrom on the succeeding beat-up 100 of the lay.

4. In a loom a substantially straight selvage loop retaining fingers having a downwardly curved rear end and mounted to slide substantially parallel with and above the edge of the fell, and means connected to the forward end of the finger acting normally to project the finger rearwardly past the fell and to retract the finger forwardly of the fell upon the beat-up of the lay, whereby, after the pick of weft toward the side at which the finger is located is beaten in and the lay moves back the finger is projected over the weft and the next pick toward the opposite side loops the weft over and around the finger, which is then withdrawn therefrom on the succeeding beat-up 105 of the lay.

5. In a loom a selvage loop retainer embodying a temple carried plate, spaced bearing arms carried by said plate, a rock shaft mounted in said bearing arms, an arm rig- 110

idly secured to the rock shaft, a loop retaining finger having one end pivotally secured to the rigidly secured arm and its opposite end capable of movement across the 5 weft threads, means for yieldingly forcing the finger in position across said threads, a stop adjustably secured to the shaft and en- gaging one of the bearing arms to limit movement of the finger in one direction, means included in the temple cap for guiding the finger, and means for moving the finger in a reverse direction.

In testimony whereof I affix my signature.

JAMES A. HENAULT.
